UNITED STATES PATENT OFFICE.

WALTHER KALB, OF LEIPZIG, GERMANY.

MANUFACTURE OF COLLAPSIBLE TUBES.

Application filed January 6, 1923. Serial No. 611,127.

To all whom it may concern:

Be it known that I, WALTHER KALB, a citizen of Germany, and resident of the city of Leipzig, Germany, have invented certain new and useful Improvements in the Manufacture of Collapsible Tubes (for which I have filed an application in Germany, August 25, 1921, Serial K. 78,888 XII 81°), of which the following is a specification.

This invention has reference to flexible or collapsible tubes such as are commonly used for the containing and dispensing of semi-liquid, viscid or liquid, powderous, or other material in a great variety of mechanical and chemical arts, and it is particularly intended to improve the construction and manipulation of containers of the kind mentioned and to reduce the costs of manufacture thereof. In the tube according to my invention the delivery aperture of the tube is controlled by a freely movable closing member in the interior of the tube which is actuated by a spring member, preferably a piece of spring wire in operative engagement with said movable closing member, and the free ends of which are disposed to become engaged with or below suitable projections, shoulders or stops arranged at the inner walls of the tube, and preferably in the vicinity of the delivery opening thereof. The said closing member which may be of globular, oval, conical, bar-like, or any other suitable shape is held against the aperture of the tube by the operation of the spring-actuating member, and is withdrawn from said aperture upon the compression of the tube by the pressure of the contents thereof around and against said closing member and the marginal aperture enclosing portions of the tube.

In the manufacture of the tube and the closing member hereinbefore referred to it is preferable to manufacture the body of the tube and the head portion thereof as a unit in one piece, ordinarily by subjecting a metal disk to a drawing operation, and by this means the bearing member for the closure and the shoulders, projections, or abutments for the spring-actuating member should preferably be manufactured in a continuous stage of operation. The closing member should then be inserted from the outside into the aperture of the tube, and

is then connected with the spring member while the latter is under tension. 55

In case the body of the tube and the head section thereof are integral with each other, the point of connection of the spring member and the closing member is not accessible from the outside, so that, under ordinary conditions, the positioning of said spring member and its connection with the closing member are rather difficult to produce. In accordance with my invention this difficulty is overcome, and a most perfect connection of said two members is obtained in an easy and rapid manner by providing a support for the spring member, and then telescopingly mounting the closing member with its fork shaped lower portion, and the tube which has been previously provided with the shoulders or projections referred to upon said, preferably axially disposed support, until said spring member with its freely exposed ends has become engaged by this movement with the recessed lower portion of the closure, and the spring has been put under tension, whereupon said spring member by the compression of the fork shaped ends of the closure by means of a kind of pincers or the like is securely connected at the interior of the tube with the closure in the closing position of the same. 70 75 80

By proceeding in this manner the connection of the closing and the spring actuating members may be effected in not more than two stages of operation. In order to further facilitate and simplify the course of manufacture, and to overcome the necessity of another stage of operation the said supporting member in accordance with my invention is constituted by a hollow body which is displaceably mounted upon a relatively stationary mandrel, and which is provided moreover with a pair of tongs, pincers or the like engageable with the spring member, the jaws of said tongs being adapted to compress the legs of the fork shaped lower portion of the closure upon the depression of the hollow supporting member. The tensioning of the spring member, its introduction into the closing member, and the connecting of the two members is effected in a single operation in accordance with my invention. Provided only separate projections on the inner wall of the tube are employed as sup- 90 95 100 105

porting abutments for the free spring acting ends of the spring-actuating member, the perfect engagement of the spring with the abutments during the mounting of the tube is insured by providing the hollow supporting member with recesses or grooves for engagement with said abutments upon the mounting of the head of the tube upon said supporting member, the spring being secured 10 in position in a slot of the support in the connecting line of said recesses. Thus the tube with the projections or abutments is positively guided, so as to become engaged with the ends of the spring. Any possibility 15 of the dropping off of the sometimes very light and thin spring wire may be further prevented by providing a retaining magnet for the spring upon the support between the recessed or grooved portions thereof. 20 The downward movement of the tube which operates the connection of the closing member with the spring may also be utilized in accordance with my invention for the, preferably simultaneously effected, cutting off the desired length of the tube. 25

Inasmuch as a thin piece of steel wire or the like which may constitute the spring-actuating member above referred to, can only be seized with difficulty, and is not very readily positioned upon the support by hand, means are provided according to my invention for the feeding of the spring wire to the support from the wire staple, and for mounting the spring upon the support. 30 With this end in view a sliding carriage is provided laterally of the means for connecting the closure with the spring member, and upon a carrier provided with clamping or holding means for the spring wire delivered 35 by the wire staple, the feeding of the carriage causing the therefrom projecting length of the spring wire which latter is retained by suitable clamping means on the carriage, to be pushed upon the supporting 40 surface of the supporting members, while upon the return stroke of the carriage the spring wire is retained by the clamping means on the supporting carrier and the clamping member of the sliding carriage is 45 caused to slide past the wire. The sliding carriage therefore acts as the means for the feeding and positioning of the spring. 50

If the carriage would be guided merely at a right angle to the supporting member or mandrel referred to, the length of spring wire projecting beyond the carriage would be disposed close to the said supporting member, which would interfere with the mounting of the tube upon said supporting member. This difficulty may be obviated according to my invention by providing for the turning of the carrier for the carriage upon the return stroke, by which means the spring wire becomes inclined with relation 65 to the supporting member. In this position

the space between the projecting length of spring wire and the supporting member is sufficiently large to allow of the unimpeded pushing or mounting of the tube.

The invention will be more fully described with reference to the accompanying drawing, showing by way of example, a machine embodying the principles of my invention. Figure 1 is a longitudinal section through a device, showing the manner of connecting the closing member with the spring, and the cutting off member for the cutting and trimming of the tube body. Fig. 2 is a side view of a portion of Fig. 1. In Fig. 3 I have shown the device in longitudinal section in accordance with Fig. 1, but in a different operating position. Fig. 4 is a plan view of part of Fig. 1, and Fig. 5 is a similar plan view of Fig. 3. In Fig. 6 the supporting member is shown in top plan view and on an enlarged scale. Fig. 7 is a longitudinal sectional view through the upper portion of the supporting member on the line 7—7 of Fig. 6; and Fig. 8 is a similar section on the line 8—8 of Fig. 6. In Fig. 9 I have shown in longitudinal section a tube, such as may for instance be obtained by the device according to this invention. Fig. 10 is a side view of the means for the feeding and positioning of the spring upon the supporting member. Fig. 11 is a view similar to Fig. 10, but in a different operative position. Fig. 12 is a front elevation, and Fig. 13 is a plan view of Fig. 10.

As shown in the drawing the body 1 of the tube which is here represented as being integral with the tube head 2 (Fig. 9) is obtained in the ordinary manner from a metal disk by a drawing operation in a tube drawing press. The tube head is provided with projections or annular or otherwise disposed shoulders serving as stops or abutments for the ends of the spring 3, the said shoulders in the form of construction shown by way of example in the drawing being constituted by two inwardly directed projections 4. The tube head 2 is, moreover, provided at the aperture of the tube with the seat 5 which operates both as a tightening and packing member as well as cutting or severing means for the contents of the tube discharged from said aperture. The seating surface 5 may be strengthened and increased by rib-like stays or fins 6, the inwardly directed surfaces 7 of which are made to conform to the seating surface of the closing member, in order to obviate the cutting of the closing member by the sharp edges of the aperture of the tube. The closing member itself in the form of construction herein shown comprises a conical valve 8 with a cylindrical shank 9 which may be easily manufactured in large quantities by means of a rivet press or a similar machine. The shank 9 is fork-shaped with two legs 10.

The connection of the closing member 8, 9 with the spring 3 is such that, when the spring is under tension, its ends engage below the shoulders 4. The means for placing the spring and the closure in this position are shown in Figs. 1 to 8, and will now be described.

A mandrel 12 is mounted on a frame 11. In the longitudinal bore 13 of the mandrel 12 a rod or bar 14 is mounted at the lower end of which a disk 15 is secured which by means of the helical spring 16 is supported on the frame 11. The upper end of the bar 14 bears on a cross-bar 17 which is displaceable in a longitudinal slot 18 of the mandrel 12, and is connected at its ends with a hollow tube like supporting mandrel 19, fitted and relatively movable on the stationary mandrel 12.

20. The hollow supporting mandrel 19 is provided with a top portion 20, the upper end of which is adapted to fit the inner peripheral outline of the tube head 2. The front surface of the top portion 20 (Figs. 6 to 8) 25 at the points corresponding to the projections or shoulders 4 is provided with recesses 21 for engagement with said projections upon the pushing of the tube 1, 2 upon the mandrel 19. In the line of connection 30 of the recesses 21 the head portion 20 possesses a slot 22, adapted to serve as a bearing for the spring 3 upon its connection with the closing member 8, 9. In the form of construction herein shown by way of example, a permanent magnet 23 may be secured in the slot 22 for magnetically retaining the spring member 3 which may consist of a piece of steel wire. Transversely with relation to the slot 22 the head portion 20 has a recess 24 in which two jaws 26 are 40 mounted which are pivoted on studs 25 and are provided with operating surfaces 27 inclined towards the axis of the mandrel, and bearing against the interior walls of the head portion 20 by the action of gravity.

45. The head portion 28 of the relatively stationary mandrel 12 is provided with two stops or lugs 29 adapted for cooperation with the jaws 26 which are retained at a certain distance above said lugs by means of the spring 16. Between the head portion 28 and the mandrel 12 intermediate pieces 30 are inserted for the shortening or lengthening of the operating length of the mandrel, said pieces 30 being detachably secured by means of threaded studs 31 or the like. Similarly, intermediate pieces or sleeves 32 are placed between the head portion 20 and the mandrel 19.

50. Upon the disk 15 and in lateral relation to the mandrel 12 two levers 34 are pivotally mounted on studs 33 and upon the extremities of these levers razor-like knife blades 35 are secured crosswise to the mandrel 12.

55. The cutting edges 36 of these blades are

shaped in such a manner that they are situated at the interior of the tube body 1 in their closing position (Fig. 5). The distance between the ends of the cutting edges 36 is somewhat less than the diameter of the tube body 1, so that the outlines of the cutting edges in the locking or closing position constitute an ellipse. Upon the lower portion of the blades 35 knives 37 are mounted in the longitudinal direction of the tube body 1, the cutting edges of which preferably project somewhat beyond the blades 36. The levers 34 are longitudinally guided on bars or stops 38 provided on the frame 11, and are forced against said bars by a spring 39. The hollow mandrel 19 is provided at its lower end with an enlargement 40 to which is connected the reduced portion 41. In the closing position of the blades 35, 37 they become engaged below the enlargement 40, and the lengths of the mandrel 12 and of the hollow mandrel 19 are so proportioned that the tube body 1 extends downwards beyond the enlargement 40.

50. The parts of the machine thus far described operate substantially in the following manner. The tube 1, 2 as delivered from the drawing press or a similar tube producing instrumentality is provided in any suitable manner with the closing member 8, 9 so that its legs 10 are situated in parallel relation to the connecting line of the two shoulders or projections 4. The wire 3 which is fed in the manner herein-after described is inserted in the slot 22 of the hollow mandrel 19, and the tube is fitted over the mandrel in such a manner that the two shoulders 4 are engaged in the recesses 21 of the hollow mandrel. As a result of the positive guiding of the parts 105 the shoulders 4 will then bear upon the free ends of the spring 3 which is thereby bent in such a manner as to become tensioned. At the same time the spring 3 is engaged between the legs 10 of the closing member 110 and at its middle portion bears against said closing member (Figs. 7 and 8). Upon then depressing the head 2 of the tube by hand or otherwise, while retaining the closing members 8, 9, the said tube 1, 2 with 115 the hollow mandrel 19 is lowered and the spring 16 is put under tension, until the stops 29 of the stationary mandrel 12 impinge against the jaws 26. The jaws are then rocked towards the inside and impinge 120 with their striking surfaces 27 against the legs 10 of the closure and compress the same, clampingly retaining the spring at about its middle portion (Fig. 3). By this means the spring is connected to the clamping member while under tension, so that it 125 pulls the closing member upon the seating surfaces 5, 7 of the tube aperture, when the tube is withdrawn from the hollow mandrel.

Upon the depression of the hollow mandrel 19 the levers 34 by their being guided along the bars 38 are turned inwardly, so as to cause the knives 35, 37 to assume their closing position (Figure 3). The ends of the cutting edges 36 of the knives 35 impinge at first upon the tube body 1 projecting beyond the enlargement 40 and produce an incision, whereupon by a kind of shearing action a ring is gradually cut off from the tube body in such a manner that the said tube body which, as manufactured in the drawing press or the like, is mostly of unequal length at its ends is evenly cut off. The knives 35, 37 during this procedure engage below the enlargement 40, and by means of the knives 37 the cut off ring or annulus is ripped open in two halves in the longitudinal direction of the tube, said halves dropping off laterally from the reduced portion 41, so as not to interfere with the mounting of the following tube. Upon releasing the tube after the depression of the hollow mandrel 19 the knives 35, 37, and the mandrel 19 are returned to their initial position by the action of the spring 16, while the jaws 26 are rocked back into the open position by gravity action.

If it is desired to manufacture another size of collapsible tube having a shorter body portion 1, it is necessary to bring the lower portion of the body into operating reach of the knives 35, 37. For this purpose it is only necessary to remove the corresponding intermediate pieces 30 from around the stationary mandrel 12, and between the mandrel and the head portion 28, and also to remove the corresponding insertion or intermediate pieces 32 from the hollow mandrel 19. The head or top portions 28 and 20 are thereby brought nearer to the knives, so that the lower part of the shorter tube body 1 projects beyond the enlargement 40, and may be cut off upon the depression of the hollow mandrel 19.

Now as regards the insertion of the wire member 3 and its feeding to the supporting mandrel 19 and its positioning in the slot 2, this may be effected by the parts of the machine, as shown particularly in Figs. 10 to 13 of the accompanying drawing. As shown in these figures a guide 42 is provided on the frame 11 of the machine for cooperation with an anvil 43 which may be actuated for instance by means of a treadle by the operator who attends to the mounting and treatment of the collapsible tube, or by machinery or by any other equivalent means, properly timed to cooperate with the above described treatment of the collapsible tube.

The upper end 44 of the anvil 43 and the upper end 45 of the guide 42 are detachably arranged, in order to be able to adapt the wire feeding means to the particular rela-

tive position of the hollow mandrel 19 in the manufacture of different sizes of tubes, the parts 44 and 45 being for instance exchanged against corresponding parts of different operating length; or the said parts 70 may be of shorter length, and may be made adjustable by suitable guides, screws and the like, not shown in the drawing, and operating in an obvious manner. Upon the part 45 of the guide 42 a supporting carrier 75 46 is secured in which a carrier 49 is pivotally mounted on a stud 47 between the eyes 48 on the support 46. At both sides of the eyes 48 two-armed levers are pivotally mounted on the stud 47. The arms 50 of said levers are connected by a cross piece 51 situated within the path of the anvil 43. By means of a spring 53 operatively related to the arms 50 and to the supporting carrier 46 the two-armed levers are forced away 80 from the mandrel 19. The other arms 54 engage between the stop pins 55 of the carriage 56 guided on the carrier 49, and movable in the direction of the mandrel 19. Upon the carrier 49 clamping and straightening means for the spring wire 57 delivered from a wire roll or staple are mounted, the said means comprising two sets of rolls 58 and 59, respectively arranged at right angles to each other, and between which the wire is guided in such a manner as to be subjected to an accurately adjustable clamping action. After its discharge from the clamping rollers 58, 59 the wire 57 is directed and guided on the carriage 56, and 90 passes below the pincers or cutting tongs 60 rockingly mounted in the carriage on the axle 61. The cutting edge 62 of the tongs 60 cooperates with the front edge 63 of the carriage in the manner of shears or pincers. 100 The tongs 60 are forced against the wire 57 with an adjustable definite clamping pressure by a spring 64. Laterally of the carrier 49 the tongs 60 are provided with two stops 65 which cooperate with stop pins 66 110 on the carrier.

The rocking movement of the carrier 49 towards the mandrel 19 is limited by the engagement of its abutting surface 67 against a stop 68 provided on the support 115 46, while upon the rocking movement of the carrier 49 in the opposite direction away from the mandrel 19 the carriage 56 engages by its abutting surface 69 with a stop 70 of the carrier 49. A spring 71 is provided 120 to insure the constant engagement of the arms 54 of the two-armed levers 50, 54 with the stop pins 55 of the carriage 56, the said spring tending to draw the carrier 49 always towards the mandrel 19. This part 125 of the machine operates substantially as follows:—In the released position of the anvil 43 the two armed levers 50, 54 and the carrier 49 are retained by the spring 53 in the position shown in Fig. 11 of the drawing, 130

the upper surface of the carriage 56 being downwardly inclined relatively to the mandrel. The spring wire 57 projects beyond the front edge of the carriage to such an extent as to present the length of the spring 3 to be connected to the closing member 8, 9. Upon now forcing the anvil upwards it impinges against the cross piece 51, and rocks the two-armed levers 50, 54 towards the mandrel 19, while placing the spring 53 under tension. By the engagement of the arms 54 with the stop pins 55 the carriage 56 is first fed forward, and at the same time the carrier 49 is rocked on the shaft 47 under the action of the spring 71, until the abutting surface 67 of the carrier becomes engaged with the lug 68. The wire supporting surface of the carriage 56 is then at the level of the slot 22 in the head 20 of the hollow mandrel 19 (Fig. 10). The carriage then proceeds on its forward feeding movement, while the projecting portion 3 of the spring wire is pushed into the slot 22. When the spring 3 is disposed in the desired position the stops 66 impinge against the stop members 65 of the pincers 60, and by means of the pincher-like co-operation of the edge 63 of the carriage 56 with the cutting edge of the tongs or pincers 60 the wire is cut off. During this forward feeding movement of the carriage 56 the spring wire 57 has been pushed forward for the amount of one wire length 3, because the spring 64 forces the tongs 60 upon the spring wire 57 with sufficient force to overcome the clamping pressure at the rollers of the clamping device 58, 59. Upon now releasing the anvil 43 the carriage 56 under the action of the spring 53 is rocked away from the mandrel 19, until its abutting surface 69 engages with the stop 70 of the carrier 49, and forces the carrier back into the position shown in Fig. 11. In this position the wire supporting surface of the carriage 56 is inclined with relation to the mandrel 19. At this return stroke of the carriage 56 the spring wire 57 has remained stationary with relation to the carrier 49, because it is prevented from moving backwards by the clamping pressure of the clamping rollers 58, 59, the tongs 60 sliding loosely past the wire. Thus, in the position according to Fig. 11 the spring wire 57 projects from the edge 63 of the feeding carriage 56 for the length of the spring wire member 3. In consequence of the inclined position of the carrier 49 the distance between the end of the spring wire and the mandrel 19 is comparatively large, so that the tube 1, 2 may be placed upon the mandrel 19 without any impediment whatever, so as to be able to connect the spring 3 which has been introduced into the slot 22 in the manner described and by the instrumentalities referred to with the closing member 8, 9.

It is therefore obvious that for the feeding and the positioning of the spring 3 in the slot 22 of the hollow mandrel 19, only a single movement of the foot of the operator is necessary, if the machine is to be operated by the workman. The operator after the insertion of the spring member 3 pushes the tube furnished by the drawing machine, and which has been previously provided with the closing member upon the supporting mandrel 19, and then by the depression of the mandrel effects the connection of the spring 3 with the closing member, while at the same time the body of the tube is cut off straight to the required length. The tube manufactured in this manner in practically only three operating stages, aside from the separate manufacture of the closing member 8, 9 is shown in Fig. 9 of the drawing.

For the manufacture of another size of tubes with shorter body, the terminal portion 44 of the anvil 43, and the guide 45 of the part 42 may be screwed off, and may be replaced by corresponding parts of such structural height that in the position of the device corresponding to Fig. 10 the wire fastening surface of the carriage 56 is at the same level with the slot 22 in the head 20 of the hollow mandrel 19 which latter in its turn has been lowered by the taking out of intermediate pieces 30 and 32 as above described.

The invention is susceptible of various other alterations and modifications to more fully adapt the same to varying conditions of application and to the convenience of the user, and within the scope of my invention. The invention is broadly applicable to the mounting of an outwardly displaceable closure in tube-like or other containers, and it is not restricted to containers with collapsible or foldable walls only; nor is the shape of the closing member of material importance, and the tensioning of the spring member and the trimming of the free end of the container may also be produced by moving said instrumentalities towards and in the direction of the closing member, and it is evident that instead of manually the device may also be operated by machinery.

I claim:—

1. The method of producing apertured containers having an outwardly projectable spring-influenced closing member, which consists in loosely mounting said closing member in the aperture of the container, mounting a spring member in the interior of said container in alinement with said closing member, moving the spring member and the closing member relatively to and into engagement with each other, tensioning said spring member and connecting it to the closing member within said container, and trimming the free end of said container.

2. The method of producing apertured containers having an outwardly projectable spring-influenced closing member, which consists in loosely mounting said closing member in the aperture of the container, mounting a spring member in the interior of said container in engagement with the sides thereof and in alinement with said closing member, moving the spring member and the closing member relatively to each other and into engagement with each other, tensioning said spring member, connecting said spring member in its tensioned position to said closing member within said container, and trimming the free end of said container.

3. The method of producing apertured containers having an outwardly projectable spring-influenced closing member, which consists in mounting said closing member in the aperture of said container, mounting a spring member in the interior of said container in alinement with said closing member, moving the spring member and the container relatively to and into engagement with each other, tensioning said spring member, connecting said spring member in the tensioned position to said closing member within said container, and simultaneously trimming the opposite free end of said container.

4. The method of producing apertured containers having an outwardly projectable spring-influenced closing member, which consists in mounting said closing member in the aperture of said container, mounting a spring member in the interior of said container in engagement with the sides thereof and in alinement with said closing member, moving the container relative to said spring member, thereby tensioning the spring member and positioning the spring member in engagement with the closing member, connecting said closing member to the spring member in the tensioned condition thereof and within said container, and simultaneously peripherally cutting the free end portion of said container and splitting the severed portion longitudinally of its length.

5. The method of producing apertured containers having an outwardly displaceable spring-influenced closing member, which consists in mounting said closing member in the aperture of said container, intermittently feeding a continuous spring wire at an angle to a form for said container, severing a certain length from said spring wire upon the upper end of said form, placing the container over the form with the closing member adjacent to and in alinement with said length of wire, moving said length of wire and said container relatively to each other to bring the wire into engagement with said closing member and to tension said length of wire, and connecting said

length of wire while under tension with said closing member.

6. The method of producing apertured containers having an outwardly displaceable spring-influenced closing member, which consists in mounting said closing member in the aperture of said container, intermittently feeding a continuous spring wire over a form for said container, severing a certain length from said spring wire upon the upper end of said form, placing the container over the form with the closing member adjacent to and in alinement with said length of wire, moving said container and said closing member relatively to said length of wire, to bring the closing member and the wire into contact and to place the wire under tension, connecting the tensioned length of wire to said closing member within said container, and withdrawing the remainder of said continuous wire at an inclination to said form.

7. A closure mounting and preparing device for automatically operated containers, having an aperture therein and a closing element displaceably mounted in the said aperture of said container, said device having in combination supporting means for said container; means for detachably retaining a spring member on said support, means engageable with said spring member for moving said support and said container relatively to each other and for tensioning the spring member, and means for connecting said spring member to said closing element.

8. A device for securing the closing element of an automatically operated container in position in the delivery aperture of said container, comprising in combination supporting means for said container adapted to project within the container, means for detachably retaining a spring member on said support, means intermediate said support and said container and engageable with said spring member for moving said support and said container relatively to each other and for tensioning said spring member, means for connecting said spring member to said closing element, and cutting means adjacent the lower end of said support for trimming the end of the container opposite to the closing element.

9. A device for securing the closing element of an automatically operated container in position in the delivery aperture of said container, comprising in combination a support adapted to telescopically receive said container thereon, means on said support for retaining a spring member adjacent the closing element of the container, and means intermediate said support and said container for moving the container and the support relatively to each other for tensioning said spring member, means mounted upon said moving means to secure said spring member to said closing element while

under tension, means for actuating said securing means, and cutting and trimming means adjacent the lower end of the support adapted to produce peripheral incisions in 5 said container.

10. A device for securing the closing element of an automatically operated container in position in the delivery aperture of said container, comprising in combination a support adapted to project within the container, means on said support for detachably retaining a spring wire between the support and the closure end of said container, means movable intermediate said support and said 15 container for moving the support and the container relatively to each other, the said movable means engaging the ends of said spring wire and adapted to tension said wire, means mounted on the said movable 20 member adapted for securing the spring wire to said closing element, knives for trimming the end of the container adjacent the lower end of said support, means for operating the knives from the said moving 25 means, wire feeding means adapted to reciprocate at an angle to the upper face of said support, and pinching and cutting means on said wire feeding means and adapted for severing and delivering the 30 spring wire from said wire feeding means to said support.

11. A device for receiving the closing element of an automatically operated container in position in the delivery aperture of said 35 container, comprising in combination a stationary support adapted to receive the container thereon, a hollow supporting mandrel movably mounted intermediate said support and said container, means for retaining a length of spring wire upon the upper end of the hollow mandrel with the ends thereof engaging the inner sides of said container and in position to engage with said closing element, clamping jaws on said 40 movable member adapted to engage a portion of said closing element, and means to operate said clamping jaws.

12. A device for securing the closing element of an automatically operated container in position in the delivery aperture of said container, comprising in combination a stationary support adapted to telescopically project into said container, a hollow supporting mandrel movable on said 50 support and intermediate the support and the container, said hollow mandrel being adapted to support a spring wire upon the upper end thereof adjacent the closing element of said container, a magnet for holding said spring wire on said hollow member, clamping means engageable with said closing element and pivotally connected to said mandrel, and stops on said support for moving said clamping means into engagement with the closing element.

13. A device for securing the closing element of an automatically operated container in position in the delivery aperture of said container, comprising in combination a stationary support adapted to project into the 70 container, a hollow supporting mandrel axially displaceable intermediate the support and the container, the said mandrel being adapted to support a spring wire upon the upper end thereof, clamping means on said mandrel adapted to engage the closing element within the container, means on said support for operating said clamping means, substantially semicircular blades pivotally mounted adjacent the lower end of said support and adapted to rock about said pivots toward said support and sever the lower end of said container. 75 80

14. A device for securing the closing element of an automatically operated container in position in the delivery aperture of said container, comprising in combination a stationary support adapted to project into said container, a hollow supporting mandrel axially displaceable intermediate the support and the container, the said hollow mandrel being adapted to support a spring wire on the upper face thereof between the mandrel and the closing element of said container, clamping means on said mandrel engageable with said spring wire and said closing element, means for operating said clamping means, substantially semi-elliptical knives adjacent the lower end of said support and arranged on opposite sides thereof, the said knives being pivotally mounted for oscillating movement toward said support, connections for operating the knives from said movable mandrel, and substantially longitudinally directed slitting knives connected to said semi-elliptical knives and adapted to split the severed portion of the container. 100 105 110

15. A device of the kind described, comprising in combination, a form adapted to support a hollow container thereon, supporting means laterally disposed relatively to said form, a carriage rockably and slidably supported on said supporting means, wire clamping and cutting means on said carriage adapted to sever a length of wire 115 upon the movement of the carriage toward said form and to release the wire upon the movement of the carriage away from said form, and means for rocking said carriage.

16. A device of the kind described, comprising in combination, a form adapted to support a hollow container thereon, wire guiding and supporting means on said form, supporting means, a wire supporting carriage rockingly and slidably mounted on said supporting means, wire clamping means on said carriage adapted for axial registration with said wire guiding means on said form, a cutting edge on said carriage adjacent said wire guiding means, and combined 120 125 130

wire clamping and cutting means on said carriage adapted for co-operation with said cutting edge when the carriage is moved toward said form and adapted to release the 5 wire on the return movement of said carriage.

17. In a device of the kind described, in combination, wire feeding means, wire cutting means adapted to sever a length of said 10 wire, an adjustable support on which said wire feeding and wire cutting means are rockingly and slidingly mounted, a stationary form adapted to enter an apertured container having a closing element positioned 15 in said aperture, wire guiding and supporting means on said form in line with said wire feeding means, means on said form for securing said severed length of wire to said closing element, and cutting means adapted 20 to engage the end of said container remote from the closing means.

18. The method of producing apertured containers having an outwardly projectable spring influenced closing member, which 25 consists in loosely mounting said closing member in the aperture of the container, placing a spring member in the interior of said container adjacent to and in alinement with said closing member, moving the spring member and the closing member relatively to one another to bring the said members 30 into engagement, and connecting the spring member to the closing member within said container.

35. 19. The method of producing apertured containers having an outwardly projectable spring-influenced closing member, which consists in mounting said closing member

in the aperture of the container, mounting a spring member in the interior of said container in engagement with the sides thereof and in alinement with said closing member, moving the spring member and the closing member relatively to each other to bring 40 said members into contact with each other, tensioning said spring member, and connecting said spring member to said closing member while in its tensioned position. 45

20. A device of the character described having in combination a form adapted to support a container having an apertured end through which a closing element may be inserted into said container, means for feeding a containing strip of wire to the upper face of said form, means for severing a length 50 of wire from said strip, and means for securing the severed length of wire to that portion of the closing element projecting with- 55 in said container.

21. In a device of the character described 60 comprising a stationary support for an apertured container having a closing element positioned in the aperture thereof, a hollow mandrel surrounding said support and adapted to slide longitudinally thereof, the 65 said hollow mandrel being provided with a slot on the upper end thereof, an oscillating wire feeding device for feeding a continuous length of wire into said slot, means for severing a length of wire from said continuous 70 strip, and means for securing said severed length of wire to said closing element within the container, the said securing means being operated by the movement of the mandrel relatively to said support. 75
